UNITED STATES PATENT OFFICE.

HARRIS L. HEES, OF TORONTO, ONTARIO, CANADA.

CURTAIN POLE.

Application filed June 15, 1923. Serial No. 645,559.

To all whom it may concern:

Be it known that I, HARRIS LINCOLN HEES, a subject of the King of Great Britain, and a resident of the city of Toronto, in the 5 county of York, in the Province of Ontario, Canada, have invented certain new and useful Improvements in Curtain Poles, of which the following is the specification.

My invention relates to improvements in 10 curtain poles and the object of the invention is to devise a curtain pole in which the means for supporting the curtains therefrom will be concealed. A further object is to devise an improved means for supporting the curtains from the pole.

My invention consists of a curtain pole constructed and arranged all as hereinafter more particularly described and illustrated in the accompanying drawing in which:

20 Fig. 1 represents a front elevation of a pair of curtains showing the same supported from a pole constructed according to my invention.

Fig. 2 is a rear elevation of the same.

25 Fig. 3 is an enlarged cross sectional view through the curtain pole.

Fig. 4 is a perspective detail of the curtain pole broken away intermediately.

Fig. 5 is a perspective detail of one of the 30 rollers and supporting members to which the top of the curtain is secured.

Fig. 6 is a perspective detail of a modified form of supporting member for holding the curtains in which the hook replaces the 35 eye at the lower end of the form shown in Figure 5, and

Fig. 7 is a perspective detail of a further modified form of supporting member in which the lower portion is provided with a 40 safety pin instead of a hook or eye.

Like characters of reference indicate corresponding parts in the different views.

1 is the pole which is preferably constructed of C shaped cross section with a 45 longitudinal slot 2 in its concealed face. The pole is secured in the usual manner to the wall as by the brackets 3. 4 are rollers adapted to be inserted into the interior of the pole, one side of each roller having a recess 5 adapted to receive the enlarged head

6 of the supporting member 7 which extends centrally through each roller, each supporting member being turned downwardly and terminating in an eye 17 as is clearly illustrated. The roller is freely rotatable about 55 the upper portion of the supporting member. The depending supporting members are secured to the curtains 8 by any suitable means such as the hooks 9.

In the modified form illustrated in Figure 60 6 the lower end of the curtain supporting member 7 is provided with a hook 18 which is directly hooked to the curtain instead of having to use a hook 9 as above described. In the further modification illustrated in 65 Figure 7 the hook 18 is replaced by a safety pin 19 which is also directly attached to the top of the curtain.

From the above description it will be seen that I have devised a simple and effective 70 curtain pole and concealed means for supporting the curtains thereon. When the curtains are in position as is illustrated in Figure 2 it is obvious that when they are pulled aside the rollers 4 will roll in the 75 pole and thus the curtains will be capable of any desired lateral adjustment.

What I claim as my invention is:

The combination with a curtain, of a curtain pole of C-shaped cross section with a 80 longitudinal slot in its concealed vertical face, a roller movable longitudinally in said pole, and its periphery engaging the internal lower surface of the pole, said roller having a central horizontal orifice therethrough communicating with an enlarged concentric recess in the face of the roller adjacent to the outer vertical face of the pole, a curtain supporting member of substantially inverted L-shape having its horizontal 85 leg extending freely through the slot in the pole, being positioned to be out of contact with the lips of such slot and extending through the central orifice in the roller into the enlarged recess therein where it terminates in an enlarged head, and means on the vertical leg of the curtain supporting member for attaching it to the curtain. 95

HARRIS L. HEES.
